PADDING ATTACHMENT FOR GARMENT HANGERS

Jerome S. Kivett, Kansas City, Mo.

Application October 10, 1949, Serial No. 120,531

1 Claim. (Cl. 223—92)

1

This invention relates to a protector for garments of the kind capable of being attached to conventional garment hangers and positioned and formed to prevent misforming of the shoulders of such garments as they are supported by the hanger.

It is the most important object of the present invention to provide a garment protector having an elongated dish-like body for overlying and covering a portion of the lowermost end of the inclined lengths of a conventional garment hanger, the protector being provided with means therewithin for frictionally engaging the hanger and holding the same in place.

Another object of the present invention is to provide a garment hanger as above set forth, wherein the dish-like body is provided with a plurality of pairs of spaced ears depending from the inner face thereof and embracing the hanger, the ears being resilient and biased toward the hanger portion to be gripped whereby to hold the entire protector on the hanger.

Other objects of the present invention include the way in which one of the aforesaid gripping means embraces an arcuate part of the hanger to hold the protector against rotative movement on the hanger; the way in which the entire dish-like body is formed not only at the top thereof but along the down-turned edges or flanges to conform to the shoulder of a garment; and many more minor details of construction to be made clear or become apparent as the following specification progresses, reference being had to the accompanying drawing, wherein:

Fig. 1 is a side elevational view of a conventional garment hanger showing a pair of padding attachments for such hanger, mounted thereon and made in accordance with my present invention.

Fig. 2 is an enlarged inverted plan view of one of the attachments per se.

Fig. 3 is a cross-sectional view taken on line III—III of Fig. 2 showing a portion of the hanger mounted therewithin.

Fig. 4 is a transverse, cross-sectional view taken on line IV—IV of Fig. 3 looking in the direction of the arrows.

Fig. 5 is a view showing the uppermost end of one of the attachments.

Fig. 6 is a transverse, cross-sectional view taken on line VI—VI of Fig. 3; and

Fig. 7 is a transverse, cross-sectional view taken on line VII—VII of Fig. 3.

It is quite well known that conventional hangers, particularly the kind that are made from a

2

single piece of wire, are, when placed in use, not entirely satisfactory because of the fact that the same tends to "cut into" the shoulders of the garment thereby presenting an unattractive crease. The damaging effect to the garment including the shoulder pads thereof and the shoulders generally, can be eliminated through use of a protector of the kind about to be described. Such protector is adapted for mounting on a hanger such as illustrated in Fig. 1 of the drawing and broadly designated by the numeral 10. However, it will hereinafter appear that the protector might well be adapted for virtually any type of clothes hanger of the kind shown in Fig. 1 whether or not the same is of wire formation.

The protector per se comprises a dish-like, hollow body 14. Body 14 is provided with a top wall 16 taking the substantially elliptical shape illustrated in Fig. 2 and including a pair of longitudinal edges 18 and 20 that diverge as one rounded end 22 thereof is approached.

The opposite end of the wall 16 is also rounded as at 24 but the arc of the end 22 is appreciably greater than that of the end 24. The top wall 16 of the body 14 is provided with a continuous down-turned flange 26 integral with the top 16 and projecting from the edges 18, 20, 22 and 24. It is noted that the flange 26 is flared outwardly with respect to the wall 14 throughout the entire length of the flange 26. Also, as illustrated clearly in Figs. 3 to 7 inclusive, the points of merger 18, 20, 22 and 24 between the top 16 and the flange 26, are rounded or arcuate. The width of the flange 26 is greatest adjacent the end 22 of the top wall 16 and such thickness of the flange 26 progressively decreases as the end 24 is approached. Consequently, the two longitudinal stretches of the flange 26 that are integral with the edges 18 and 20 of top wall 16, are identical and progressively decrease in width as illustrated in Fig. 3 as the end edge 24 of wall 16 is approached.

The entire dish-shaped body 14 is placed upon one of the inclined lengths 28 or 30 of the hanger 10 in covering relationship thereto and adjacent horizontal stretch 32 of the hanger 10.

The flange 26 is cutaway into a notch 34 at the end 24 thereof for clearing the stretch 28 or 30 of hanger 10 as the case may be and as illustrated in Fig. 3 of the drawing. Consequently, that part of the hanger within the body 14 rests upon the innermost face of the wall 16.

It is noted also that hangers 10 are conventionally provided with a rounded portion 36 that interconnects the stretches 28 and 30 with the

stretch 32. Accordingly, the end 22 of flange 26 is rounded in conformity with such rounded portion 36 to provide a complementary fit.

The innermost face of top wall 16 of body 14 is provided with a pair of opposed, down-turned ears 38 and 40, spaced just inwardly from the notch 34 and preferably integral with the wall 16. Normally, the distance between the ears 38 and 40 is less than the diameter of the wire from which hanger 10 is made and the entire body 14 is made of resilient material to the end that the stretch 28 or 30 may be forced in place between the ears 38 and 40. Through such resilient character of the ears 38 and 40, the stretch 28 or 30 will be gripped tightly and further held against the inner face of wall 16 through the medium of upwardly facing shoulders 42 on the proximal faces of the ears 38 and 40. The shoulders 42 therefore, underlie the proximal portion of the hanger 10 and therefore, hold the same in place.

A pair of ears 44 and 46 are likewise formed on the innermost face of wall 16 and depend therefrom adjacent the end 22. The ears 44 and 46 extend downwardly and outwardly toward the flange 26 in portions 48 and 50 rigid with the flange 26, as illustrated in Figs. 2 and 3. Down-turned ears 44 and 46 are likewise provided with shoulders 52 on the proximal faces thereof and facing upwardly for underlying the proximal portion of the hanger 10 and holding the same against the inner face of wall 16. Ears 44 and 46 being integral with the resilient wall 16 are normally spaced a distance less than the diameter of the wire from which hanger 10 is made and, therefore, grip the same when the body 14 is in place. It is seen that through the portions 48 and 50 of the ears 44 and 46 embracing and receiving a portion of the arcuate end 36 of the hanger 10, body 14 will be held in place and against tipping or rotative movement on the respective stretch 28 or 30.

The entire protector 12 is easily snapped into place upon the hanger 10 as desired and may be left thereon indefinitely as desired. When the hanger 10 is placed in use with a pair of the protectors 12 thereon in the manner illustrated in Fig. 1, such protectors 12 will receive and underlie the shoulders and shoulder pads of virtually any type of garment and thereby protect the same throughout the time that the garment is thus supported.

The oval shape of the wall 16 and the inclined or arcuate flange 26 thereof, conforms to the shoulder and holds the same in its normal intended contour. There are no sharp edges or other projections that will tend to produce a crease or other unattractive conformation in the garment as the same hangs on the support 10.

It is contemplated that the entire body 14 be molded or otherwise formed from a suitable attractive plastic in various colors but it is understood that other materials might well be used,

preferably of a resilient character to the end that the ears 38 and 40 and 44 and 46 will yieldably grip the hanger and hold the entire body in place during use.

Manifestly, the protector may be made inexpensively, attractively and when finished ready for use, the same will be light, easy to use and easy to apply or remove from the hanger 10 or hangers of such character as desired.

Slight modifications may be made in the protector herein illustrated either for use with a hanger such as shown or similar types of hangers without departing from the spirit of this invention as defined by the scope of the appended claim.

Having thus described the invention, what is claimed as new and desired to be secured by Letters Patent is:

For a wire garment hanger having a normally horizontal stretch, an inclined length, and an arcuate end portion, a garment protector comprising an elongated, dish-shaped body of resilient material adapted to overlie said inclined length of the hanger and having a flat top wall, a continuous downturned flange provided with a notch at one end thereof for receiving said inclined length of the hanger, and an arcuate portion at the opposite end of the body conforming in shape to and engaging said arcuate end portion of the hanger; a pair of spaced clips depending from and integral with said top wall adjacent the notch; a second pair of clips depending from the top wall and integral therewith adjacent said opposite end of the body; and a pair of spaced portions interconnecting the second pair of clips and said arcuate portion of the body and embracing said arcuate end portion of the hanger for holding the body against rotative movement on said inclined length of the hanger, said clips being provided with opposed shoulders adapted to underlie said inclined length of the hanger for holding the same biased against the lowermost face of said top wall of the body, the shoulders on the second pair of clips adapted to engage the arcuate end portion of the hanger to cooperate with said arcuate portion of the body in holding the body against reciprocable movement on said inclined length of the hanger.

JEROME S. KIVETT.
